Primary Examiner — Austin Murphy(74) *Attorney, Agent, or Firm* — Rader, Fishman & Grauer PLLC**CLAIM**

The ornamental design for a portable information terminal, as shown and described.

DESCRIPTION

FIG. 1 is a perspective view of front, top and right side of a portable information terminal showing my new design; FIG. 2 is another perspective view of rear, top and left side thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The portions of the article in broken lines are shown for illustrative purposes only and form no part of the claimed design.
